UNITED STATES PATENT OFFICE.

ARNOLD STORUD, OF FARM PARK RIVER, NORTH DAKOTA.

BOB-SLED.

1,272,562.

Specification of Letters Patent. Patented July 16, 1918.

Application filed June 29, 1917. Serial No. 177,748.

To all whom it may concern:

Be it known that I, ARNOLD STORUD, a citizen of the United States, and resident of Farm Park River, in the county of Walsh 5 and State of North Dakota, have invented a certain new and useful Improvement in Bob-Sleds, of which the following is a specification.

The present invention relates to vehicles, 10 and more particularly to the mounting and bracing of runners for bob sleds.

An object of the present invention is to provide an adjustable connection for runners to hold the same in various transversely 15 spaced-apart positions for varying the tread of the vehicle and to accommodate it to widely and closely spaced-apart ruts in a roadway.

Another object of the present invention is 20 to provide an improved mounting and connection for the body bolsters of the vehicle to retain the same on the runners at all adjustments of the latter.

The above, and various other objects and 25 advantages of this invention will be in part described, and in part understood, from the following detailed description of the present preferred embodiment, the same being illustrated in the accompanying drawings 30 wherein:—

Figure 1 is a side elevation of the running gear of a bob sled constructed according to the present invention.

Fig. 2 is a top plan view of the same, the 35 body bolsters being removed.

Fig. 3 is a transverse section, enlarged, taken on a transverse plane indicated by the line 3—3 in Fig. 1.

Fig. 4 is a horizontal section taken in a 40 plane indicated by the line 4—4 of Fig. 1.

Fig. 5 is a detail vertical section taken through one of the forward cross bars in a plane indicated by the line 5—5 of Fig. 1, the runners being omitted.

Fig. 6 is a similar view taken on a plane 45 indicated by the line 6—6 in Fig. 1, the runners being omitted.

Fig. 7 is a detail perspective view of one 50 of the supporting blocks and an adjacent sleeve or head adapted to seat upon the same, the block and the head being shown separated.

Referring to these drawings, 10 designates 55 a pair of forward runners which may be of wood, and of any suitable configuration, and provided with shoes 11 in the usual manner.

Each runner 10 is provided, intermediate its ends, with a pair of spaced-apart upstanding tie rods 12 engaging at their upper ends through the intermediate portion of an upwardly arched brace strap 13, the latter being downturned at its opposite end and engaging flat against the upper edge of the adjacent runner 10, and held thereto by clips or straps 14 secured against the opposite sides 60 of the runner 10.

A block 15 is seated upon the upper edge of the runner 10 between the pair of rods 12 and is provided with a substantially T-shaped head which extends transversely of 70 the block, and which is arranged upon the upper end thereof. The block 15 is provided at its opposite sides with pairs of vertically extending and spaced-apart outstanding ribs 16 providing a space between each 75 pair of the ribs adapted to snugly receive the rods 12 therein. Heads 17, in the form of sleeves, are seated upon the upper ends of the blocks 15, and corresponding in width to that of the blocks 15. Each head 17 is 80 provided at opposite sides with a pair of vertically extending and spaced-apart ribs 18 adapted to align with the ribs 16 and engage against the opposite sides of the rods 12. A clamping plate 19 is placed upon the 85 upper side of the head 17 and is provided with pairs of spaced-apart lugs 20 at opposite sides adapted to register in vertical alinement with the ribs 16 and 18. The lugs 20 hold the plate 19 from longitudinal dis- 90 placement from between the rods 12. The upper ends of the rods 12 are provided with clamping nuts or the like which engage against the upper side of the strap brace 13, and which bind the base securely against the 95 plate 19, and hold the rods 12 from spreading apart.

The heads 17 are connected by a transversely extending bar 21 which fits snugly in the heads 17 at opposite ends and which is 100 adapted to slide therethrough. The bar 21 is provided with rows of vertically disposed openings 22 near its opposite ends through which may be secured retaining bolts 23, the latter passing vertically through the inner ends of the heads 17 and through the adjacent end portions of the plate 19. Clamping nuts or the like are mounted upon the bolts 23 to hold the same in position, the bolts 23 securing the heads 17 from longitudinal movement on the opposite ends of the bar 21. The heads 17 may thus be ad- 105 110

justed longitudinally upon the bar 21 to vary the width or tread of the runners 10. A body bolster 24, provided with indentations at opposite ends, is seated upon the intermediate portion of the bar 21, and held thereto by bolts 25, or the like. The body bolster 24 is provided at its opposite ends with standards 26, or the like, for retaining logs and other articles to be carried on the bob sled.

The forward ends of the runners 10 are connected together by an adjustable device which is in the form of an intermediate sleeve portion 27, to the opposite ends of which are fitted slidable sections 28, the latter carrying outstanding spindles 29. The spindles 29 are adapted to engage through transverse apertures formed in the forward upturned ends of the runners 10, and are held in the apertures by clamping nuts or the like as shown in the drawings. The slidable sections 28 are held in the sleeve 27 by retaining bolts 30 which pass through the opposite ends of the sleeve 27, and are engaged through anyone of a series of openings 31 formed in the inner ends of the slidable sections 28.

The intermediate sleeve section 27 is provided upon its upper side with a boxing 32 which opens transversely across the sleeve 27 and which is adapted to receive the inner end of a pole or beam 33. A bolt 34 passes vertically downward through the boxing 32 and the sleeve 27 for securing the tongue 33 in the boxing and for reinforcing the sleeve section 27. The pole or beam 33 is provided at opposite sides with outwardly and rearwardly inclined brace sections 35 formed of strap metal or the like which are secured to the pole 33 by a transversely extending bolt 36. If inner brace sections 37 are formed of strap metal, and are adapted to engage at their outer ends against the sides of the outer brace sections 35, the brace sections 35 and 37 being provided with apertures adapted to register for the longitudinal adjustment of the brace sections with respect to each other, and adapted to receive clamping bolts 38 therethrough, the clamping bolts 38 being secured in place by winged nuts 39 or the like. The inner ends of the brace sections 37 are bent substantially at right-angles to the longitudinal axis of the forward brace and are adapted to engage upon the opposite ends of the end sections 28 of the brace.

The rear runners 40 are preferably of similar construction to the runners 10 and are connected together intermediate their ends in the same manner, and by the same devices as above disclosed in connection with the runners 10. The rear runners 40 also support a bolster 24 which is aligned horizontally with the forward bolster 24 and is adapted to constitute the body portion of

the bob sled for supporting logs or the like by resting upon the bolsters, or for supporting any suitable body structure which may be employed.

The forward ends of the runners 40 are connected together by an adjustable brace comprising the intermediate sleeve 27 and the slidable end sections 28 with their adjacent parts, the spindles 29 of the slidable sections 28 engaging through the forward ends of the runners 40 for securing the same together.

A reach or beam 41 is preferably engaged in one side of the rear sleeve 27, and is held therein by a retaining bolt 34, and the reach or beam 41 is secured to the forward adjustable brace of the rear runners by the longitudinally adjustable brace bars 35 and 37 as above described. The forward end of the reach 41 is provided with a clevis 42, or the like which is secured by an eye 43 to the rear end of the forward cross bar 21.

By the use of this construction of bob sled the runners 10 and 40 may be quickly adjusted to accommodate the bob sled to the desired tread, or to the transversely spaced-apart ruts in the road over which the bob sled is to travel. This may be quickly accomplished by merely withdrawing the bolts 23 and sliding the heads 17 along the opposite ends of the cross bars 21 into the desired position, and again placing the bolts 23 in position. The bolts 30 of the forward brace bars are also correspondingly adjusted to the opposite ends of the sleeves 27 for the purpose of retaining the sliding sections 28 in the desired adjusted position corresponding to the adjustment of the heads 17 upon the ends of the brace bars 21. It will be noted that by the peculiar arrangement of the spaced-apart rods 12, the same do not have to be removed, or any parts adjusted thereon, as the latter engage between the ribs 16 and 18 of the blocks 15 and the heads 17. The mountings therefore remain undisturbed, and the adjustment may be quickly had by merely removing and replacing the bolts 23 and 30.

The beams 33 and 41 may be secured to the sleeves 27 as shown in Fig. 5, or as shown in Fig. 6, one being a slight modification of the other and being preferably arranged in the forward and rear braces as above set forth.

It is of course understood that various changes and modifications may be made in the structure and design of the various above specifically described parts without departing from the spirit of this invention, and being restricted only by the scope of the following claims.

I claim:

1. In a runner mounting, the combination of a pair of longitudinally spaced-apart rods upstanding from the runner, a block fitting between the rods, a head fitting between the

- rods above the block and having a transverse aperture therethrough, said block and head being provided with spaced-apart vertically extending ribs outstanding from the opposite sides thereof for engagement against the opposite sides of said rods, a transverse brace bar engaging at its end through said head, and means for securing the end of said brace bar adjustably in the head.
- 10 2. In a runner mounting, the combination of a pair of upstanding rods adapted to be mounted on a runner, a supporting block arranged between the rods and having vertical guideways to receive the rods for holding the block from lateral displacement from the rods, a connecting head resting on the block between the rods, brace plates secured to the sides and top of the head and having vertical ways therein to receive the rods, and a clamping element mounted on the upper ends of the rods for binding the brace plates to the head and holding the latter to the block and for maintaining the rods in the vertical guides and ways.

ARNOLD STORUD.
